W. E. VILLINGER,
AUTOMATIC STAY ARM.

APPLICATION FILED JULY 24, 1919.

1,385,626.

Patented Mar. 30, 1920.

FIG. 1.

FIG. 2.

FIG. 3.

Inventor

UNITED STATES PATENT OFFICE.

WILLIAM E. VILLINGER, OF WILLIAMSPORT, PENNSYLVANIA.

AUTOMATIC STAY-ARM.

1,335,626.

Specification of Letters Patent. Patented Mar. 30, 1920.

Application filed July 24, 1919. Serial No. 313,065.

To all whom it may concern:

Be it known that I, WILLIAM E. VILLINGER, a citizen of the United States of America, residing at Williamsport, in the county 5 of Lycoming and State of Penn., have invented certain new and useful Improvements in Automatic Stay-Arms, of which the following is a specification.

The primary object of the present invention is the provision of a lid holding and releasing device, for phonograph and other cabinets, the same being automatic in its 10 operation and not likely to become accidentally detached or released.

15 A further object of the invention is to provide a support for the cover or lid of a talking machine cabinet, adapted for operation upon grasping and moving the lid without the necessity of engaging the hand of the 20 operator, with the invention.

With these general objects in view, my invention consists of a device that is easy and inexpensive to manufacture, and will be hereinafter fully described, in connection 25 with the accompanying drawing.

In the drawing, forming a part of this application, and in which like reference characters designate corresponding parts throughout the several views,

30 Figure 1 is a vertical longitudinal sectional view through a cabinet, in its open position, illustrating my invention installed thereon,

Fig. 2 is a front elevation thereof, with the 35 cover removed, and

Fig. 3 is a perspective view of the safety mechanism employed for the stay arm, detached from the cabinet.

Broadly considered, my invention is serv- 40 iceable in connection with cabinets such as 10 having a cover 11, hinged to one upper edge thereof, as 12, the invention being for the purpose of retaining the cover open, when desired, retained against accidental 45 closing but readily released, and closed manually. A hanger 13 is secured in substantially the usual manner, interiorly of the cover 11, having the stay arm or bar 14 pivotally depending therefrom.

50 The cabinet 10 is provided with a motor board 15 with a slot 16 adjacent one side of the cabinet 10 adapted for the reception of a plate 17 through said slot, secured to the side of the cabinet as by screws or other 55 suitable means. A guide plate or flange 18 carried at right angles at one end of the

plate 17 overlies the slot 16 being secured by screws 19 upon the board 15. A longitudinal slot 20 in the plate 18 is adapted for the reception of the bar 14 therethrough, for 60 longitudinal movement during the opening and closing of the cover 11.

An inverted V-shaped stop 21 is struck-up from the plate 11, while a hook-shaped supporting dog 22 is pivoted to the plate 17 65 by a post 23 in such a manner as to position one side or arm 24 of the stop 21, within the recess or indented side 25 of the hook 22. The dog 22 is capable of swinging relatively of the stop 21, a stud 26 upon the plate 17, 70 limiting the outward movement of the dog 22 when swinging away from the stop 21, while the upper end portion 27 engages the stop near its apex 28 limiting the inward swinging movement of the dog. 75

The stop 21 having a portion 29 connecting the same to the plate 17, the dog 22 is positioned in substantially the same vertical plane as the stop 21 by placing a washer 30 upon the post 23, between the plate 17 and 80 dog 22. An angularly projecting pin 31 adjacent the free end of the bar 14, is accommodated by a notch 32 at the outer side of the slot 20 during the intended complete withdrawal of the bar 14, outwardly through 85 the slot 20 or the admission thereof, inwardly through said slot, when assembling the device.

With the invention assembled, as shown in Figs. 1 and 2 of the drawing, the initial entering of the lower end of the bar 14, through the slot 20 with the pin 31 passing through the notch 32, will bring said pin 31 upon the downwardly curved upper side 33 of the stop 21 permitting the bar 14 to pass 90 downwardly for closing the cover 11. Upon swinging the cover to its open position, the bar 14, is elevated through the slot 20 until the pin 31 engages the throat or socket 34 preventing further upward movement of 100 the cover and bar, and upon permitting the bar to lower, the pin 31 will seat in the indented side 25 of the dog 22, for resting with the cover 11 held open, as best shown in Fig. 1 of the drawing. 105

When desiring to close the cover 11, the bar 14 is further elevated, by swinging the cover 11 rearwardly upon its hinges 12, bringing the pin 31 against the inner edge 35 of the dog portion 27 and swinging the dog away from the stop 21 until the pin 31 enters a recess in the upper end of the 110

dog 22. The bar 14 is prevented from leaving the slot 20 by the pin 31, and upon releasing the hand from the cover 11, the weight thereof will force the bar downwardly and tilt the dog 22 forwardly, passing the pin 31, out of the shallow recess 36 forwardly, and downwardly over the face 33 of the stop as heretofore described. The curved upper end 37 of the dog portion 27, 10 acts as a stop to prevent the pin 31 from moving rearwardly of the dog 22, and the inclination of the bar 14 causes the weight of the cover 11 to automatically move the bar and its pin 31 downwardly during the 15 closing of the cover 11.

The complete operation of the invention will be apparent from this detailed description thereof, the repeated opening and closing of the cover 11 taking place without any 20 liability of the pin 31 passing accidentally through the slot 32, and while the dog support 22 supports the cover open, against accidental closing, the cover is readily opened and closed at will, by the operator.

25 While the form of the invention herein set forth is believed to be the preferable embodiment thereof, it is nevertheless understood that changes may be made therein, without departing from the spirit and scope 30 of my invention. The plate 17 with its flange 18 and stop 21, are preferably formed integral of sheet metal, bent and struck-up in the positions described.

What I claim as new and desire to secure 35 by Letters Patent is:—

1. A cover support for cabinets, comprising in combination with the swinging bar carried by the lid of the cabinet, a pin upon the bar, a stationary stop adapted for initial 40 engagement by the pin, during both the closing and opening of the cover, and a swinging hook-shaped dog adjacent the stop adapted for the seating reception of said pin within said dog, when the cover is opened.

45 2. In combination with a cabinet having a lid, a support bar pivotally depending from the cover, a plate carried by the cabinet, having a fixed inverted V-shaped stop, a hook-shaped dog pivoted on said plate, 50 adjacent the stop, and a pin projecting from the bar adapted for downwardly sliding

over the stop during the closing of the cover, and for engaging within the throat of the stop, when the cover is elevated, whereby the subsequent fall of the bar positions said pin 55 supportingly within the indented side portion of the dog.

3. In combination with a cabinet having a hinged cover, a swinging bar upon the cover, a perpendicularly mounted pin adjacent the free end of the bar, a plate carried by the cabinet, a stop upon the plate, adapted for the engagement by the pin, during the upward movement of the bar, upon opening the cover, a supporting dog 60 pivoted to the plate, adapted for the seating reception of the pin, when the cover is opened, and for engagement by the pin during the upward movement of the cover, during the closing of the lid whereby the dog 65 is swung rearwardly permitting the pin to move forwardly and downwardly, over said stop.

4. A cover support for cabinets, comprising a bar pivotally attached to the cover 75 of the cabinet, with a pin adjacent its free end, a stationary stop and a swinging dog upon the cabinet, the dog having an indented side, adapted for the seating reception of said pin when the cover is opened, the stop 80 having a curved side upon which said pin is adapted to ride, during the lowering of the bar and the closing of the cover, the said dog having a recess adjacent its upper end substantially upon a level with the top of 85 the stop, adapted for guiding said pin onto said curved side of the stop.

5. In combination with a cabinet having a hinged lid, a swinging support bar carried by the lid, a plate in the form of a 90 slotted guide carried by the cabinet, having an entrance side notch for the slot thereof, a projecting pin upon the bar adapted to pass through said notch during the entrance and exit of the bar, through the slot of said 95 plate, a pivoted supporting dog beneath said plate adapted for the seating reception of said pin, when the cover is opened, and a guide stop for the pin adjacently fixed relatively of the dog.

In testimony whereof I affix my signature.
WILLIAM E. VILLINGER.
